UNITED STATES PATENT OFFICE.

WALTER FERRIER, OF ELYRIA, OHIO.

NOSE-FORMING MACHINE.

Application filed October 16, 1919. Serial No. 380,999.

To all whom it may concern:

Be it known that WALTER FERRIER, citizen of United States of America, residing at Elyria, in the county of Lorain and State of Ohio, has invented new and useful Improvements in Nose-Forming Machines, of which the following is a specification.

The primary object of the invention is to provide a machine of the type designed for 10 forming a nose on a tank, tube or the like, wherein the action of the rolls on the end of a tank or tube is such as to swage the metal down by a triple rolling process, thereby increasing the thickness of the wall of the 15 nose so that the area of any transverse cross-section will be the same at any point on the nose, and to the further end that the tip forming the extremity of the nose, and which is designed to be bored and tapped 20 for the reception of the customary valve nipple, shall be of sufficient thickness and stability to afford a substantial seat for attachment.

Heretofore in the nosing of tanks and similar receptacles the tendency has been for 25 the action of the mechanism to cause a reduction in the thickness of the wall and at the same time a reduction in the tip or extremity of the nose, with the result that the 30 tank is weakened at the nose end and affords an insufficient support for the nozzle tapped thereinto, and it is therefore the object of the present invention to provide means for causing the contraction or drawing together 35 of the wall under such conditions as to condense and thicken rather than to draw out and reduce the wall, and to this end to provide forming elements carried by the head, for contact with the nose portion of the 40 receptacle which shall act progressively and continuously in a direction substantially perpendicular to the surface of that portion of the wall of the receptacle which is receiving the pressure and to follow the movement 45 of the wall as it is forced inward to maintain this perpendicularity of pressure.

With these and related objects in view, having special reference to associated parts of the mechanism, and more particularly 50 those parts involving the chuck and the means for presenting the receptacle to the head and maintaining the same in the proper relation therewith, the invention consists in a construction, combination and relation of

parts of which a preferred embodiment is 55 illustrated in the accompanying drawing, it being understood that changes in form, proportion and details may be resorted to within the scope of the appended claims without departing from the principles involved. 60

In the drawing:

Figure 1 is a longitudinal sectional view of the machine.

Figure 2 is a plan view of the same.

Figure 3 is a transverse sectional view on 65 the plane indicated by the line 3-3 of Fig. 1.

Figure 4 is an enlarged detail sectional view of a portion of the spinning head showing one of the planetary forming elements in dotted and full lines respectively in its initial and advanced positions. 70

Figure 5 is a detail sectional view on the plane indicated by the line 5-5 of Fig. 4.

Figure 6 is a further detail section on the 75 plane indicated by the line 6-6 of Fig. 4.

Figure 7 is a transverse sectional view on the plane indicated by line 7-7 of Fig. 1.

Figure 8 is a detail view of one of the 80 contour plates.

Figure 9 is a transverse sectional view through the chuck on the plane indicated by 9-9 of Fig. 1.

Figure 10 is a longitudinal sectional view in detail of the chuck advancing hydraulic 85 cylinder.

Figure 11 is a transverse sectional view of the cylinder shown in Fig. 10 on the plane indicated by the line 11-11 of Fig. 1. 90

The spinning head which is illustrated in detail in Figs. 3, 4 and 5, and is shown in operative relation with the other parts of the mechanism in Figs. 1 and 2, embodies a shell 20 in which is mounted a plurality of planetary forming elements consisting of 95 rollers 21 adapted to be moved in orbital paths around the axis of the head in the revolution of the latter, said shell having hub 22 secured in any suitable and substantial manner to a driving shaft 23 to which motion may be communicated as through 100 gears 24 and 25 from a suitable motor 26 which, obviously may be of the electrical or any other available type.

The driving shaft is mounted in suitable 105 bearings carried by the pedestals 27 which are preferably seated upon and keyed as at 28 to a base or bed plate 29 which also pref-

erably serves as the support for the motor, to the end that independent vibration in the transmission of motion from the motor to the shaft may be minimized or eliminated.

5 The planetary rollers constituting the forming elements have their reduced spindle portions 30 and 31 mounted in bearings formed in carriers 32 which are pivotally mounted upon the shell of the head, as with 10 in a projecting sleeve 33 thereof, for swinging movement in radial planes and progressive inward movement as the action upon the nose end of the tank or other receptacle proceeds, and in practice it is preferred to cause 15 the inward progress or swinging movement of the carriers and hence the forming rollers by fluid pressure as through cylinders 33' in which are separate pistons 34 connected by links 35 with the carriers.

20 Fluid pressure, either pneumatic or hydraulic may be communicated to the outer ends of the cylinders through passages 36 formed in the shell of the spinning head in communication with ports 37 leading from 25 an axial channel 38 formed in the driving shaft 23 and adapted terminally as indicated at 39 to be connected with any suitable source of pressure or supply.

In Fig. 1 there is shown at 40 a tank or receptacle which is to be nosed, the same being held in place by clamps 41 shown in detail in Fig. 7, and engaged at its bottom or closed end by the chuck 42. The fixed or stationary jaws 43 of said clamps may be 35 supported by pedestals 44 as shown while the movable jaws 45 are carried by levers 46 fulcrumed at 47 and having counterbalancing weights 48. A plurality of clamps, spaced apart as shown, is preferred in order 40 that the tank may be positioned therein and substantially supported prior to bringing the chuck into engagement with the closed end thereof, and in order that the jaws of the clamp may properly engage and fit the 45 contour of the tank or receptacle, according to the diameter of the receptacle which is to be nosed, contour plates 49 and 50 are arranged in the seats provided in said jaws, the contour plate 49 of the upper jaw being 50 secured in place by set screws 51 while the contour plate 50 of the lower jaw is properly positioned with reference to that of the upper jaw by means of wedges 52. When a tank or receptacle of considerably smaller 55 diameter is to be nosed a contour plate of the construction illustrated in detail in Fig. 8 may be employed and which is provided with an extension or ear 53 provided with openings 54 for engagement by screws or 60 other fastening devices to lock it in place. The operation of the movable members of the clamps to properly and forcibly engage the tank or receptacle interposed between the jaws thereof is preferably effected by fluid 65 pressure supplied by a suitable distributing

pipe 55 to a cylinder 56 in which is arranged a piston 57 connected by rod or link 58 with said lever.

The chuck which serves to advance the tank or receptacle in opposition to the pressure of the nose forming elements is constructed as shown in the drawing of a cup 59 in which is arranged a halved ring 60 and a bearing disk 61, of which the former is adapted for adjustment in the cup by 75 means of centering screws 62 adapted to provide for a proper alinement of the tank or receptacle axially with the spinning head, and said chuck is carried by a slide 63 mounted upon guides 64 on a base or bed 80 plate 65 which also serves to support a cylinder 66 preferably keyed as at 67 to the base and containing a piston 68 of which the rod 69 carries the chuck. The chuck is thus adapted for advance and return movement 85 by fluid pressure and in order to limit the movement thereof to that which is necessary to accomplish the desired operation a liner 70 may be arranged in the cylinder as shown. Obviously similar liners may be arranged in 90 the other cylinders of the mechanism to limit the movements of the pistons to avoid loss of time and pressure.

Referring to those ends of the forming rolls which extend toward the tank or receptacle as the latter is advanced, as the "forward" ends thereof, said rolls are enlarged toward their rear ends and are shaped to form concaved side faces, and the pivotal points 70 of the carriers by which the rollers 100 are supported are arranged eccentrically as to the rollers or out of alinement with the axes thereof, so that as the rollers are advanced inwardly by the means provided to actuate the carriers, they receive a movement 105 which is a combination of a pivotal or swinging movement and an endwise or axial movement. In other words by reason of the eccentric mounting of the carriers with reference to the rollers the latter in their advancement in the progress of the work, and while traveling in radial paths due to the swinging movement of the carriers, have a rocking movement which is endwise or in planes parallel with the axis of the tank or receptacle and hence of the spinning head, so that the tendency of the roll in its inward movement as the nosing of the tank progresses is to crowd the metal of the tank wall both inwardly and longitudinally of the tank or toward the bottom thereof, the roll having a rocking movement which brings different portions of the length of its surface into bearing contact with the surface of the tank wall and progressively and constantly in a 115 direction which is perpendicular to the surface at the point of contact. The result of this action is to avoid the drawing or spreading out of the metal constituting the wall of the receptacle and to condense or press 120 125 130

- the metal of the wall axially toward the bottom of the receptacle and therefore to increase rather than decrease the thickness of the wall and consequently the stability of the 5 nose and the amount of the material concentrated at the tip portion of the nose as shown at 71 where the tapped bore is subsequently formed for the reception of the outlet nozzle of the tank.
- 10 Moreover, in order to provide for adaptation of the head to tanks or receptacles of widely varying dimensions, diametrically, the pivot pins 70 which constitute the bearings of the carriers are supported by hangers 15 72 consisting of bolts which extend radially through the wall of the collar 33 and are engaged in contact with the inner and outer surfaces thereof by nuts 73 and 74, or the equivalents thereof, to the end that the pivotal points of the carriers may be adjusted 20 radially with reference to the head and thus modify the direction of bearing of the rolls with reference to the length of the tank to the end that a greater or less endwise pushing 25 or condensing effect of the rolls with reference to the tank end may be produced to correspondingly modify the tendency to increase rather than reduce the thickness of the wall of the tank at the nose portion 30 thereof. Obviously any suitable form of anti-friction bearing may be provided for the terminals of the rolls in the carrier to adapt them to turn freely as the revolution of the head proceeds, and to secure rigidity 35 of mounting the carriers may be provided with guiding webs 75 operating between parallel cheeks 76 suitably located within the head in contact with the webs.
- Moreover in order to ensure the displacement 40 of the tank or receptacle as the chuck is backed or withdrawn by the operation of the piston 68 in the cylinder 66, a push rod 77 may be arranged in an axial bore 78 of the piston rod 69 to extend terminally 45 through a suitable opening 79 in the base of the cup for contact with the bottom of said tank. Thus after nose forming operation has been completed and the chuck is backed to withdraw the tank from the spinning 50 head the push rod serves to eject the tank from the chuck and leave it supported in the clamps 41 by which it is automatically released upon the relief of pressure in the cylinders 56 owing to the fact that the counterbalancing weights 48 will serve to raise 55 the movable jaws of said clamps.
- What is claimed as new and useful is:
1. A spinning head for nose forming machines having planetary forming elements, carriers for the same disposed when actuated to impart a continuous radial inward movement to the rear ends of said elements and an initial inward movement and subsequent outward movement to the forward 60 ends of said elements, and means for simultaneously actuating said carriers during rotation of the head.
  2. A spinning head for nose forming machines having planetary forming rolls, carriers therefor pivotally mounted for progressive inward movement in radial planes and having their pivot points disposed within the lengths of the carriers, and means for imparting movement to the carriers during the rotation of the head. 70
  3. A spinning head for nose forming machines having planetary forming rolls, carriers therefor pivotally mounted eccentrically to the rolls for progressive movement in radial planes with their pivot points disposed within the lengths of the rolls, and means for simultaneously actuating said carriers during the rotation of the head. 75
  4. A spinning head for nose forming machines having planetary forming rolls, carriers therefor pivotally mounted near one end of each roll and within the length of the latter, and means for imparting simultaneous progressive inward movement to the carriers at the opposite ends of the rolls. 80
  5. A spinning head for nose forming machines having planetary forming rolls, pivotal roll carriers for swinging movement in radial planes relative to the head, and means for varying the pivotal points of said carriers in planes radial to the head. 90
  6. A spinning head for nose forming machines having planetary forming rolls, roll carriers pivotally mounted for swinging movement in radial planes relative to the head, and hangers supporting said carriers and mounted in the head for adjustment in planes radially thereof. 100
  7. A spinning head for nose forming machines having a shell, planetary forming rolls, hangers adjustably connected with the shell for movement in planes radial thereto, roll carriers pivotally mounted upon said hangers for swinging movement in radial planes relative to the head, and means for imparting progressive inward movement to the carriers. 105
  8. A spinning head for nose forming machines having a rotary shell provided with radially disposed fluid pressure cylinders having parallel guide cheeks and a forwardly projecting collar, hangers mounted in said collar for adjustment in radial planes relative to the axis of the head, roll carriers pivotally mounted upon said hangers for swinging movement in radial planes relative to the head and provided with arcuate guide webs for cooperation with the guide cheeks, and pistons operating in said cylinders and connected respectively with said carriers. 115
  9. A nose forming machine having a spinning head and means for operating the same, a chuck mounted for movement axially in relation to the spinning head, fluid actuated means for operating the chuck and including 120
  - 65 130

a piston having an axially channeled rod connected with the chuck and a push rod mounted in said channel for terminal projection into the chuck upon the retraction of the latter.

10. A nose forming machine having a spinning head and means for actuating the same, a chuck mounted for movement axially in relation to the head and means for communicating advance and return movements to the chuck, said chuck being provided with a receptacle receiving cup, a bearing ring fitted within said cup, and radial centering devices for adjusting said ring in the cup.
11. A nose forming machine having a spinning head and means for actuating the same, a pressure actuated chuck mounted for movement axially in relation to the spin-

ning head, means for ejecting an article from the chuck on the return movement of the latter, and clamps interposed between the chuck and the spinning head and having fixed and movable jaws having counterbalancing weights and fluid actuated operating means. 20 25

12. A nose forming machine having a spinning head and means for actuating the same, a chuck and operating devices therefor, and means interposed between said chuck and head for supporting an object to be nosed, said means having fixed and movable jaws and means for operating the latter and interchangeable contour plates removably seated in said jaws.

In testimony whereof he affixes his signature.

WALTER FERRIER.
